UNITED STATES PATENT OFFICE.

HENRY L. ZABRISKIE, OF WESTFIELD, AND FREDERICK DIEHL, OF ELIZABETH, NEW JERSEY, ASSIGNEES TO DIEHL MANUFACTURING COMPANY, OF ELIZABETH, NEW JERSEY, A CORPORATION OF NEW JERSEY.

ELECTRIC FAN.

1,115,147.

Specification of Letters Patent. Patented Oct. 27, 1914.

Application filed February 27, 1913. Serial No. 731,182.

To all whom it may concern:

Be it known that we, HENRY L. ZABRISKIE and FREDERICK DIEHL, citizens of the United States, residing, respectively, at Westfield and Elizabeth, in the county of Union and State of New Jersey, have invented a certain new and useful Improvement in Electric Fans, of which the following is a full, clear, and exact description.

10 This invention relates to electric fans, and more particularly to fans of the oscillating type in which the motor body with fan blades and fan guard is pivotally mounted upon a stationary base, and is made to oscillate slowly by means of reducing gearing actuated by the armature shaft. This gearing mounted upon the motor body and acting through a link connection with the stationary base, imparts an oscillatory motion to the pivotally mounted parts.

In fans of the oscillating type it has been customary to mount the gearing which produces the oscillatory effect in a separate casing upon the outside of the motor casing, thus making the fan to a certain extent unsightly in appearance; and as the appearance of the fan is of importance, one of the objects of this invention is to mount the oscillating gearing upon the motor body so that it will not cause an unsightly protuberance and will not destroy the general contour of the fan.

One portion of our invention, designed to meet these contingencies, consists in a self-contained gearing feature characterized by the gear train being housed in a compartment arranged and concealed within the motor casing, and deriving motion from the armature shaft by connection therewith at a point located between the motor bearings.

As fans of this type are subject to various conditions of use and are likely to have their oscillatory movement obstructed, it is necessary to provide some form of safety device to prevent stripping of the operating gearing or stalling of the armature and the burning out of the motor windings; and to this end the invention comprises a safety clutch interposed in the oscillating mechanism and set to yield under excessive strain and permit the cessation of oscillation while the motor continues to run.

Another object of the invention is to provide means whereby the arc of oscillation

may be varied or the oscillations be completely stopped at the will of the operator and while the fan is in motion; and in furtherance of this object, the invention consists of a link connected to a rotary crank disk by means of a disk mounted in the crank disk so as to be adjustable toward and from the center of said crank disk.

In the accompanying drawings illustrating the invention, in the several figures of which like parts are similarly designated, Fig. 1 is a side elevation of a fan embodying the elements of this invention, with a part of the casing broken away to show the oscillating mechanism. Fig. 2 is a rear end view with the outer casing removed to show the oscillating gearing. Fig. 3 is a view taken on line A B, of Fig. 1, and looking in the direction of the arrow. Fig. 4 is a bottom plan view of the rotary crank disk with a part of the connecting link broken off. Fig. 5 is a vertical section taken on line C D, of Fig. 4. Fig. 6 is a view similar to Fig. 4, but broken away to show the spring-pressed pawl. Fig. 7 is a top plan view, partly in horizontal section, on line E F of Fig. 5. Figs. 4 to 7 are drawn on a larger scale than the other views.

1 is the fan base, having a bottom flange 2, by which it may, if desired, be fixed rigidly to its support; but, of course, the base, 35 bracket, or stand may be of any suitable construction and adapted to the position in which the fan is to be used.

3 is the motor body, having an outer casing, composed of a central exterior portion 4 and end portions or caps 5 and 6. Within this casing is the motor housing, preferably composed of a central portion 7 and end portions 8 and 9 secured together by screws 10.

11 is a part of the motor field, and 12 is the armature mounted on the armature shaft 13. On the outwardly projecting end 14 of the shaft 13 is mounted the usual fan 15 in closed in a guard 16.

The oscillating gearing is located within a compartment 17; formed by an enlargement of the end portion 9 of the motor housing and between the armature 12 and the rear bearing 18 for the armature shaft. This enlargement of the end portion 9, with its cap 105 hereinafter mentioned, constitutes what, for sake of brevity, is herein referred to as the oscillating-gear box. This gearing is com-

posed of a worm 19 formed upon a sleeve secured, as by set screws 20, to the armature shaft 13, and this worm meshes with and drives a worm wheel 21 fixed on the upper end of a spindle 22 which has fixed to it near its lower end a spur pinion 23. The pinion 23 drives a spur gear 24 mounted to revolve on the upper end of a spindle 25, and this spur gear 24 has a spur pinion 26 fastened to it and turning with it on said spindle. This spur pinion 26 drives the spur gear 27 secured by set screws 28 to a shaft 29 bearing in a sleeve extension 30 of the compartment 17. As shown, these pinions and spur gears vary in diameter so as to reduce the speed, and they are herein referred to collectively as a worm-driven reducing gearing for effecting the oscillation of the fan.

The compartment 17 is provided with a cap 31 containing the armature shaft rear end bearing 18, and this cap may be suitably secured over the compartment 17 by screws 32, one of which is shown in Fig. 2.

At the lower end of the shaft 29 is mounted a crank disk 33, having a hub 34, in which is transversely arranged a spring pawl 35 adapted to engage one or more notches 36 in the shaft 29. The shaft 29 turns in the direction indicated by the arrow in Fig. 7, and it will thus be seen that the driving engagement between the shaft 29 and crank disk 33 is purely frictional, and if any strain should be placed upon the crank disk greater than the tension of the spring pawl the frictional engagement between shaft 29 and crank disk would allow the shaft 29 to rotate free of the crank disk, and thus the gearing would not be stripped nor the motor windings be burnt out.

For the purpose of varying the arc of oscillation of the fan, the under side of the crank disk 33 is provided with a crank carrier, here shown as a ratchet disk 37 eccentrically mounted therein with respect to shaft 29 and the teeth 38 of this disk 37 are engaged by a spring-pressed pawl 39 provided with a shoulder 40 and mounted transversely in the crank disk 33. 41 is link, one end of which is connected with the ratchet disk 37 at a distance from the center of the ratchet disk 37 equal to the distance of its center from the center of the shaft 29, and the other end of said link is connected with the base 1, as by screw stud 42. For purposes of adjustment the wrist-pin or screw stud 43 which connects the link 41 with the ratchet disk 37 has a projecting knurled head which may be readily grasped by the fingers of the operator when he desires to change the arc of oscillation. By arranging the pivotal point of the link 41 as above described, it is evident that that point may be placed directly under the center of the shaft 29 and in that way cause the oscillations to cease, although the gearing is still running.

It is also evident that by adjusting the ratchet disk 37 the arc of oscillation may be varied from zero to the full crank throw, in which latter position the ratchet disk is shown in the drawings.

The base 1 may be provided with a swiveling connection 44 for the motor body, so that the fan may be set at any desired angle with relation to its base, and the current of air from the fan thereby directed at any angle, up or down, within a certain arc.

The central section 4 of the outer casing has fixedly secured to its under side by rivets 45 a spindle 46 which extends into the socket piece 47, and this spindle has a shoulder 48 which rests upon and turns on a ball-thrust or other suitable bearing 49.

By using the gearing above described and inclosing it within the motor casing, an oscillating electric fan is produced which is neat in appearance, and free from the unsightly casing protuberances used to contain the oscillating mechanism in fans of this type now on the market.

The arc of oscillation may be adjusted from zero to the full crank throw while the fan is running, and this adjustment will be permanent because the ratchet disk 37 can be moved in only one direction. Furthermore the pawl 35 will abut against the shoulder of the notch 36 when the adjustment of the ratchet disk is being made, thus preventing relative movement between the parts at that point.

It is not necessary that tools be used for adjusting the arc of oscillation or arresting oscillation since both operations, by adjusting the ratchet wheel, may be effected by hand acting upon the knurled head on the screw stud 43.

It is to be understood that the invention is not limited to the particular details of construction shown in the drawings, for various changes may be made in the construction without departing from the scope of the invention.

What we claim is:—

1. In an electric fan of the oscillating type, the combination of a motor having an armature and an armature shaft, a motor casing, a motor housing inclosed within the casing, said housing having an end portion provided with a box-like enlargement located between the armature and the rear bearing for its shaft and forming a compartment, oscillating gearing arranged within said compartment and geared to the armature shaft, a normally disposed rotary shaft extending outside of the compartment and casing and operatively connected with the gearing in the compartment, a crank-disk applied to said outside shaft, and means to convert the rotary motion of the outside shaft into an oscillating motion of the fan.

2. In an electric fan of the oscillating

type, the combination of a motor having an armature and an armature shaft, a motor casing, a motor housing inclosed within the casing, said housing having an end portion provided with a box-like enlargement located between the armature and the rear bearing for its shaft and forming a compartment, oscillating gearing arranged within said compartment and geared to the armature shaft, a cap fitted tight to said compartment to thereby conceal the inclosed gearing, a rotary shaft driven by said gearing and extending outside of the compartment and casing and provided with a crank-disk at its outer end, and means applied to said disk to convert its rotary motion into an oscillating motion of the fan.

3. In an electric fan of the oscillating type, the combination of a motor having an armature and an armature shaft, a motor casing, a motor housing inclosed within said casing, said housing having a gear-box located between the armature and the rear bearing of the armature shaft, reducing gearing arranged in said gear-box and operatively connected with the armature shaft, a normal shaft operatively connected with the gearing in the gear-box and extending thence outwardly through said gear-box and casing, a crank-disk on the outer end of said shaft, a base on which the described mechanism is mounted so as to be capable of turning thereon axially, and means reactively connecting said crank-disk and the base to effect the oscillation of the fan.

4. In an electric fan, an oscillating mechanism actuated by the fan motor, and including a link, a crank disk, and a crank carrier to which the link is eccentrically pinned and mounted in said crank disk and adapted to be turned in one direction only to vary the radius of the link with respect to the crank disk, combined with an automatically operating safety device interposed between the crank disk and its operating mechanism and

itself operative in a direction of rotation opposite to that in which the crank carrier is turned for adjustment.

5. In an electric fan, a base, an oscillating mechanism actuated by the fan motor and including a link pivoted at one end to the base, a rotary crank disk, and a crank-carrier eccentrically mounted in the crank disk and to which the other end of the link is eccentrically pinned, said crank-carrier adapted to be turned in one direction only to vary the radius of the link with respect to the crank disk, combined with an automatically operating safety device interposed between the crank disk and its rotating mechanism and itself operative in a direction of rotation opposite to that in which the crank-carrier is turned for adjustment.

6. In an electric fan of the oscillating type, the combination of a motor having an armature and an armature shaft, a motor casing, a motor housing inclosed within the casing, said housing having an end portion provided with a box-like enlargement located between the armature and the rear end bearing for its shaft and forming a compartment, oscillating gearing arranged within said compartment and geared to the armature shaft, a cap provided with the said rear end bearing and covering in said compartment, a rotary shaft driven by said gearing and extending outside of the compartment and casing and provided with a crank-disk at its outer end, and means applied to said crank-disk to convert its rotary motion into an oscillating motion of the fan.

In testimony whereof we have hereunto set our hands this 26th day of February, A. D. 1913.

HENRY L. ZABRISKIE.
FREDERICK DIEHL.
